CLAIM

The ornamental design for a hand-held scrubbing device, as shown and described.

DESCRIPTION

FIG. 1 is a right side elevational view of a hand-held scrubbing device showing our new design;

FIG. 2 is a top plan view thereof;

FIG. 3 is a front elevational view thereof;

FIG. 4 is a rear elevational view thereof;

FIG. 5 is a bottom plan view thereof;

FIG. 6 is a left side elevational view thereof;

FIG. 7 is a perspective view thereof with a handle of the scrubbing device being positioned in a first orientation with respect to a main body portion thereof; and,

FIG. 8 is a perspective view thereof with the handle being positioned in a second orientation relative to the main body portion of the scrubbing device.

The parts shown in broken lines in FIGS. 7 and 8 are shown for illustrative purposes only and form no part of the claimed design.
